UNITED STATES PATENT OFFICE.

RICHARD T. BOND, OF COALGATE, OKLAHOMA.

COMBINATION-TOOL.

No. 893,602.

Specification of Letters Patent. Patented July 21, 1908.

Application filed April 12, 1907. Serial No. 367,772.

To all whom it may concern:

Be it known that I, RICHARD T. BOND, a citizen of the United States, residing at Coalgate, in District 23, Oklahoma, have invented 5 a new and useful Combination-Tool, of which the following is a specification.

The present invention relates to improvements in devices adapted for use about a stove, and it has for its object to provide a 10 device that is adapted for use not only as a lifter for the lids or covers, but it is also adapted for use in handling hot pans, kettles, and other parts that would otherwise require the use of a cloth to prevent burning of the 15 fingers.

To these and other ends, the invention consists in certain improvements and combinations and arrangements of parts, all as will be hereinafter more fully described, the 20 novel features being pointed out more particularly in the claims at the end of the specification.

In the accompanying drawing, Figure 1 is a perspective view of a combination tool of 25 the character described and constructed in accordance with the present invention. Fig. 2 is a view of a portion of the tool showing the jaws in coöperative relation for engagement with a stove lid. Fig. 3 represents a 30 longitudinal section of a portion of the tool showing the mounting for the relatively movable jaws. Fig. 4 is a view similar to Fig. 3, showing the construction and method of mounting the relatively movable handle 35 portion or grip. Fig. 5 is a sectional view showing the mode of lifting the flanged pans with an implement constructed in accordance with my present invention.

Corresponding parts in the several figures 40 are indicated throughout by similar characters of reference.

The device in the present embodiment of the invention is especially adapted for use in handling stove lids, when the jaws are in 45 closed relation, and by reason of the relative movement of the jaws the device is adapted for use in the handling of pots, pans and other cooking vessels, and it comprises, in the present instance, a shank having an intermediate portion 1 which is substantially 50 U-shaped in cross section to form a pair of longitudinal guiding flanges, a semi-cylindrical portion 2 at one end and adapted to form a handle grip, and having a toe 3 at its 55 opposite end which is offset from the intermediate portion and arranged at a suitable

angle to enter the usual aperture in the stove lids, this toe also serving the purpose of a gripping jaw. The material in rear of the toe 3 is cut away at 4 in order to admit the 60 latter to the aperture in the stove lid, and the portion 5 connecting the toe to the shank or intermediate portion is provided with a longitudinally extending slot 6 into which is fitted the attaching portion 7 of the jaw 8, a 65 rivet or other suitable pivot 9 serving to support the jaw so as to move into and out of coöperative relation with the jaw formed by the part 3.

The jaw 8 between the attaching portion 70 and the flat engaging portion is preferably curved upwardly and rearwardly relatively to the tool in order to receive the flange on a pan that is engaged between the two jaws, and the attaching portion of the jaw 8 is provided with a recess or socket 10 arranged eccentrically of its pivot, and coöperating with this recess or socket is a head or projection 11 formed on the forward end of an operating bar 12, the latter being guided to reciprocate 75 longitudinally between the flanges of the intermediate portion 1.

Any suitable means may be employed for reciprocating the actuating bar in order to effect the desired movements of the relatively movable jaw, but it is generally preferable to manipulate the jaw by variations in the gripping action of the operator's hand on the handle of the device, and the actuating bar is shown as so actuated in the present 80 instance, a complementary grip 13 being provided to coöperate with the grip 2 on the shank, the grip 13 being pivoted to a relatively fixed portion of the shank, as at 14, and provided with a rigid crank-shaped portion having a laterally turned projection or head 15 adapted to coöperate with a correspondingly formed recess or socket 16 formed in the rear end of the actuating bar, the proximating movement of the grips 2 and 13 85 under the grasp of the hand serving to proximate the jaws 3 and 8, and a separating movement of the grips producing a corresponding movement of the jaws. In the present instance, a spring is shown for automatically separating the grips when the hold of the hand is released, the spring shown consisting of an intermediate convolution or coil 17, and the arms 18 and 19 forming continuations of the free ends of the coil, the extremities of these arms being turned laterally 90 as at 20 and 21, so that they will extend in 100 105 110 115

opposite directions and rest in the apertures 22 and 23 formed in the grips 2 and 13, respectively. The normal action of the spring operates to spread the arms 18 and 19, and 5 the latter, engaging at the inner sides of the hand grips, serves to produce a corresponding action on the latter, serving to open them and the jaws. The method of mounting the spring is advantageous in that its action 10 serves to retain its laterally turned ends in coöperative relation with the apertures in the grips, and in manufacturing the device, the spring can be readily applied by merely springing its ends into these apertures, and, 15 of course, in case of breakage, the parts may be readily disengaged and removed.

In using the device as a lifter for stove lids or covers, the hand grips are drawn together by a grasp of the hand, the projection 15 of 20 the relatively movable grip coöperating with the actuating bar to move the latter forwardly, the projection 11 on the actuating bar coöperating with the recess in the relatively movable jaw and causing a movement 25 of the latter toward the jaw 3, and when the jaws are in proximate position, they may be readily inserted into the usual opening in the stove lid, and the latter may be handled as desired, and in cases wherein the openings of 30 the lids are worn, the inwardly extending projections may be engaged between the jaws. Whenever it is desirable to move pans, pots, and other culinary utensils from place to place, or to position them upon the 35 stove, the flange or other projecting part of the article to be lifted or moved is inserted between the jaws of the device and gripped thereby as pressure is applied to the hand grips, the article being immediately released 40 at the moment the hand grips are released from the operator's hand. Moreover, an implement of the character herein described may be manufactured so cheaply that it may be sold at a low price, as its parts may be 45 cast of malleable iron with sufficient accuracy to enable them to properly fit together, the pivots for the movable jaw and hand grip serving as locks to retain the coöperating parts of the jaw and grip and the actuating 50 bar or member in coöperative relation, so that only two rivets are employed and the springs may be readily applied by merely compressing their ends during their insertion

between the grips, and when their out-turned ends spring into the apertures in the 55 grips, accidental disengagement of the spring will be prevented.

Of course it will be understood that the device shown and described is merely one embodiment of the invention, and that modifications may suggest themselves that do not depart from the spirit of the invention.

What is claimed is:—

1. A tool of the character described comprising a shank channelled longitudinally, a 65 slotted toe at one end of the shank, a substantially semi-cylindrical fixed handle section extending from the other end of the shank, a fixed jaw extending from the toe, a movable jaw pivotally connected to the toe and extending through the slot, said jaw having a recess, a movable handle section pivotally mounted within and having its edges housed between opposite edges of the fixed handle section, said movable section having an integral crank portion provided with a head, a push bar slidably mounted within the channelled shank and held against lateral displacement thereby, said push bar having a recess for the reception of said head, and having a head disposed to project into the recess within the movable jaw, and means housed within the handle sections for holding said sections normally in a predetermined relation. 70 75 80 85

2. The combination with a longitudinally channelled shank, a slotted toe at one end thereof, a fixed jaw extending from the toe, a substantially cylindrical, contractible handle at the other end of the shank; of a movable jaw pivotally mounted within the toe and extending through the slot, said jaw being bowed adjacent the toe, a push bar within and guided by the shank, means operated by the contraction of the handle for actuating 95 the push bar to shift the movable jaw in the direction of the fixed jaw, and resilient means within the handle for holding the same normally extended. 90

In testimony that I claim the foregoing as 100 my own, I have hereto affixed my signature in the presence of two witnesses.

RICHARD T. BOND.
